SHOE AND FOOT LENGTH COMPARATOR

John N. Crandall, St. Louis, and Glenn A. Richardet, St. Louis County, Mo., assignors to Brown Shoe Company, Inc., St. Louis, Mo., a corporation of New York

Application January 5, 1952, Serial No. 265,096

3 Claims. (Cl. 33—3)

1

This invention relates to devices for determining shoe length which will provide a proper fit, and is particularly concerned with devices for visually comparing shoe length with foot length.

A principal object of the present invention is to provide a simple and easily operated device by which shoe length may be visually compared with foot length.

It is an object also to provide a visual shoe size determining device which is direct reading and capable of being placed in a shoe so that shoe size and length may be determined without placing the foot in the shoe, thereby avoiding the unsanitary shoe try-on method.

The invention herein preferred consists in a frame constructed of any suitable material, heel stops on the frame in spaced relation, one for cooperation with a shoe to be measured and the other for cooperation with the foot which is to be compared to shoe length, and a slide member which is movable on the frame in such a manner as simultaneously to indicate the shoe size in cooperation with one of the heel stops during actual shoe length measuring cooperation with the other heel stop.

The invention furthermore consists in the parts and elements, and in the combination of parts and cooperation thereof as will hereinafter be more particularly described when considered with the accompanying drawing, wherein:

Fig. 1 is a side view of the preferred shoe length to foot length comparing device adjusted for determining the length of a shoe, the shoe being shown in broken outline;

Fig. 2 is a similar view of the present device shown in position for comparing foot length with shoe length, a foot being disposed on the device as shown in broken outline;

Fig. 3 is a front elevational view of the present device showing details of its construction;

Fig. 4 is a transverse section taken at line 4—4 in Fig. 3;

Fig. 5 is a transverse section taken at line 5—5 in Fig. 3;

Fig. 6 is a fragmentary plan view of one end portion of the present device seen at line 6—6 in Fig. 3; and

Fig. 7 is a transverse sectional view at line 7—7 in Fig. 6.

The present device for comparing shoe length with foot length consists in a frame 10 formed of any suitable material such as metal. The frame may be one piece, as shown, shaped to provide a heel stop 11, an adjacent foot receiving portion of linear aspect 12, a curved or angled por-

tion 13, and a shoe length measuring portion 14 of linear aspect together with a heel stop 15. This frame 10 is provided with the curved portion 13 so that the shoe length measuring portion 14 can be arranged at an angular relationship with the foot receiving linear portion 12 to avoid interference in inserting the portion 14 (Fig. 1) in a shoe indicated in broken outline at S.

The frame 10 carries or is provided with a slide member 17 formed of a suitable flexible material such as spring steel. The slide 17 is movable along a face of the frame 10 between the foot receiving portion 12 and the shoe length measuring portion 14. Due to the curved portion 13 of frame 10, it is desirable to have the slide formed of flexible material so that the slide can be made to traverse the curved portion.

The slide 17 is provided with a guide 18 fixed at the looped or rebent portion 19 adjacent the shoe length measuring portion 14 of the frame, and a guide 20 is also carried intermediately of the frame portion 13. The guide 18 is suitably clamped or fixed in the loop 19 of the frame as will be understood upon inspection of Figs. 1, 6 and 7. The guide 20 is secured to the frame curved portion 13 by means of a rivet 21 shown in Figs. 1 and 5.

A slide manipulating handle 23 is shown in Figs. 1, 3 and 4. The handle 23 is adapted to secure a guide 24 to the end portion 22 of slide 17 so that the handle 23 and associated guide 24 move with the slide 17 along the linear portion 12 of frame 10. It is noted that guide 24 is arranged in a reverse manner to the previously described guides 19 and 20. This arrangement of guides prevents the slide 17 from being displaced from its intended cooperating association with the frame 10.

With reference to Fig. 1, the present device is shown with the slide 17 moved to a position (full line) in which the end portion 25 thereof is retracted into the guide 19, thus producing the shoe measuring portion 14 to its minimum length. At the same time, the slide portion 22 in the guide 24 is located at a minimum spacing from the heel stop 11. The distance between the end 22 of the slide 17 in the guide 24 and the heel stop 11 is substantially the same as the minimum length of the shoe measuring portion 14. Measurement of the length of the shoe S is carried out by inserting the portion 14 into the shoe with the heel stop 15 located against the inner face of the shoe heel. After this is accomplished, the handle 23 may be manipulated to project the end portion 25 of the slide 17 forwardly (dotted outline) into

the toe of the shoe S. The combined length of frame portion 14 and the projected end portion 25 of the slide 17 indicates the interior length of the shoe S. Movement of the slide 17 to project slide end 25 the required distance, simultaneously moves the slide end 22 and associated guide 24 away from the heel stop 11 a like distance, thereby giving visual indication of a length which is equal to the determined length of the shoe.

In Fig. 2 the present device is shown in its position for comparing visually the length of the foot F with the distance marked out on the frame portion 12 between the heel stop 11 and the adjusted position of the slide end portion 22, this adjusted position being determined in accordance with the manipulation of the device described in connection with Fig. 1. For example, if a determined shoe length A is indicated at the right in Fig. 2, this same length will also be indicated at A' in the left portion of Fig. 2. The foot F may now be placed on the linear portion 12 of frame 10 to visually compare its length with the shoe S. The distance B equals the recommended growth space or clearance for a shoe properly to fit the foot F. If the distance B is too great or insufficient, as determined by direct observation of the present device, a different shoe size is at once indicated.

Referring to Fig. 3, the present device may be provided with indicia along the upper face of the foot receiving portion 12 so that the slide 17 during its adjusting movement on the frame will serve to uncover the indicia and thereby make it easy to read directly a shoe size which has a length proper for a given foot length. This not only avoids the uncertain fitting of a shoe by its "feel," but avoids the usual requirement that the foot be inserted in the shoe during shoe selection and fitting. The present device is especially useful for fitting shoes made on different lasts or for fitting shoes formed on the same last where some variations are bound to occur. Normally shoes having similar size markings, but formed on different makes of lasts, differ in actual internal length so that some shoes feel longer or shorter than other shoes of a similar size. The present device readily indicates the last variations and permits the selection of a shoe of proper length regardless of the make of last used in its manufacture.

The present device has the further advantage that it can be used for any make of shoe, whereas the use of test shoes made with windows or transparent toe portions fails to account for variations in internal length of shoes made on the same lasts.

What we claim is:

1. A device for comparing shoe length with foot length comprising a frame, two heel stops including a shoe heel stop and a foot heel stop on

said frame, and an elongated length determining slide on said frame having the opposite ends thereof movable relatively toward and away from said heel stops, one of said slide ends and said shoe heel stop determining the shoe length and the other slide end and said foot heel stop establishing a similar length along said frame for direct comparison with the foot length.

2. A device for comparing shoe length with foot length comprising a frame formed from flat strip material and having a foot receiving portion, a curved portion and a shoe length determining portion, two heel stops, one for each of said foot and shoe portions of said frame, guides located along said curved frame portion, and a flexible slide movable through said guides over said curved frame portion, one end portion of said slide cooperating with said shoe length determining portion of said frame by moving toward or away from said shoe heel stop therefor and the opposite end of said slide cooperating with the foot receiving portion of said frame by moving toward or away from said foot heel stop therefor and establishing a similar length for comparison with the foot length.

3. A device for visually comparing shoe length with foot length comprising a frame formed of flat strip material having straight foot receiving and shoe length measuring portions arranged in right angular relation, two heel stops on said frame, one for each of said foot receiving and shoe length measuring portions of said frame, and a measuring slide carried by said frame and movably arranged to cooperate with said foot receiving and shoe length measuring frame portions to determine shoe length for comparison directly with foot length, said slide having one end cooperating with said foot heel stop for said foot receiving frame portion and the opposite end cooperating with said shoe heel stop for said shoe length measuring portion to establish the shoe length measurement on said foot receiving frame portion, said foot receiving frame portion having indicia thereon in position to be revealed upon movement of said slide into a shoe to be measured to indicate shoe length.
